[57] CLAIM

The ornamental design for a tire for automobiles, as shown and described.

DESCRIPTION

FIG. 1 is a front elevational view of a tire for automobile showing our new design it being understood that the tread pattern is repeated uniformly throughout the circumference of the tire as shown schematically by solid lines;

FIG. 2 is a right side elevational view thereof the left side being a mirror image of that shown;

FIG. 3 is a perspective view thereof; and

FIG. 4 is an enlarged fragmentary front elevational view thereof.
